UNITED STATES PATENT OFFICE

98,380

DESIGN FOR A SEWING KIT

Giuseppe Amato, New Britain, Conn.

Application September 7, 1935, Serial No. 58,469

Term of patent 3½ years

To all whom it may concern:

Be it known that I, Giuseppe Amato, a subject of the King of Italy, residing at New Britain, in the county of Hartford and State of Connecticut, have invented a new, original, and ornamental Design for a Sewing Kit, of which the following is a specification, reference being had to the accompanying drawing, forming part thereof.

The figure is a perspective view of a sewing kit, showing my new design.

I claim:—

The ornamental design for a sewing kit, as shown.

GIUSEPPE AMATO.
